UNITED STATES PATENT OFFICE.

WILLIAM W. HOPKINS, OF THORNTOWN, INDIANA, ASSIGNOR TO THE
HOPKINS IMPROVED SCALE COMPANY, OF SAME PLACE.

SUPPORTING DEVICE FOR SCALE-BEAMS.

SPECIFICATION forming part of Letters Patent No. 248,177, dated October 11, 1881.

Application filed January 17, 1881. (No model.)

To all whom it may concern:

Be it known that I, WILLIAM W. HOPKINS, a citizen of the United States, residing at Thorntown, in the county of Boone and State 5 of Indiana, have invented a new and useful Improvement in Portable Platform and Counter Scales, of which the following is a specification.

My invention relates to an improvement in 10 platform-scales whereby the graduated beam may be easily read from any point of view.

It consists in mounting the scale-beam or steelyard in a separate movable head adapted to rotate around the axis of the pillar through 15 which the suspension-rod descends to the levers below the platform.

It consists, further, in a swivel link or clevis connecting the scale-beam and the suspension-rod.

20 The accompanying drawings illustrate my invention.

Figure 1 is an elevation of a scale-beam or steelyard and casting supporting it and the pillar on which it is supported, the pillar being 25 partly in section. Fig. 2 is a vertical view at right angles to the first, showing the upper end of suspension-rod and its connection with the scale-beam.

20 *a* is a casting adapted to receive the bracket *b*, from which the scale-beam *e* is suspended by a link in the ordinary manner in a central position within the casting *a*. The base of cast-

ing *a* is bored out to fit over a corresponding projection, *c*, on the top of the pillar *d*, the outside of the base forming the capital to the pillar, the object being to enable the casting to sit steadily on top of the pillar, and at the same time be capable of rotation around its vertical center. 35

The scale-beam is connected to the suspension-rod *r*, and thereby to the levers below, by 40 a swivel link or clevis, *l*, in the manner clearly shown in Fig. 2.

In scales as heretofore constructed the scale-beam has been held rigidly in one position as 45 regards its relation to the platform.

With my improvement the position of the lever can be varied to suit the direction from which the light comes, or to get out of the way of surrounding objects. 50

I claim as my invention—

1. In a weighing-scale, the scale-beam or steelyard *e* and its support *a*, combined with the pillar *d* in such manner as to rotate thereon, substantially as shown and described. 55

2. In a weighing-scale, the combination of the scale-beam *e*, rotating support *a*, link or clevis *l*, and suspension-rod *r*, as and for the purpose set forth.

WILLIAM W. HOPKINS.
